CLAIM

The ornamental design for a floral wrapper, as shown and described.

DESCRIPTION

FIG. 1 is a top plan view of a first embodiment of our new floral wrapper design;

FIG. 2 is a bottom plan view thereof;

FIG. 3 is a left side elevational view thereof;

FIG. 4 is a right side elevational view thereof;

FIG. 5 is an upper end plan view thereof;

FIG. 6 is a lower end plan view thereof;

FIG. 7 is a perspective view thereof;

FIG. 8 is a top plan view of a second embodiment of our new floral wrapper design;

FIG. 9 is a bottom plan view thereof;

FIG. 10 is a left side elevational view thereof;

FIG. 11 is a right side elevational view thereof;

FIG. 12 is an upper end plan view thereof;

FIG. 13 is a lower end plan view thereof; and,

FIG. 14 is a perspective view thereof.

The broken line showing of flowers is for illustrative purposes only and forms no part of the claimed design.

The floral wrapper has no substantial thickness.
